PLURAL COMPARTMENT WINDOW CONTAINER
AND BLANK THEREFOR
Charles E. Palmer, Somers, Conn., assignor to Monsanto
Company, a corporation of Delaware
Filed Aug. 6, 1963, Ser. No. 300,331
9 Claims. (Cl. 229—27)

The present invention relates to window containers, and more particularly to a novel plural compartment window container and the blank therefor.

It is an object of the present invention to provide a plural compartment container having a windowed compartment for displaying goods received therein and an unwindowed compartment for receiving accessory items such as premiums or relatively non-displayable fittings.

Another object is to provide such a container which is relatively strong and durable and wherein the windowed compartment is resistant to pilfering and the unwindowed compartment is readily accessible for replacing or inserting accessories such as fittings and premiums.

It is also an object to provide a blank for a plural compartment window container which is relatively economical to manufacture and relatively simple to erect.

Other objects and advantages will be readily apparent from the following detailed description and claims and the attached drawings wherein:

FIGURE 1 is a perspective view of a double compartment window container embodying the present invention with one wall flap of the unwindowed compartment opened for clarity of illustration;

FIGURE 2 is a sectional view to an enlarged scale along the line 2—2 of FIGURE 1;

FIGURE 3 is a plan view to a reduced scale of the blank for the container of FIGURE 1;

FIGURE 4 is a perspective view of another container embodiment of the present invention with the end wall flap of the unwindowed compartment opened for clarity of illustration; and

FIGURE 5 is a plan view to a reduced scale of the blank for the container of FIGURE 4.

It has now been found that the foregoing and related objects may be readily attained by a container having a frame of relatively rigid and opaque sheet material with a plurality of hingedly connected wall panels defining the several sides of the container and an interior partition wall dividing the interior of the container into two compartments. Adjacent wall panels of one of the compartments have an aperture therein which extends across the hinged interconnection therebetween to provide a large window opening in the one compartment. A window of semi-rigid synthetic plastic sheet material extends across the window aperture and has a linear fold therein generally in alignment with the hinged interconnection between the apertured wall panels. The window is dimensioned larger than the aperture and is located within the frame so that marginal portions of the adjacent panels about the aperture overlap opposed side margins of the window generally normal to the direction of the linear fold therein. Means such as adhesive secure the window to the frame along the overlapping side margins. To secure the partition wall in position, one or more flaps are provided thereon which are secured to other panels.

In accordance with the preferred aspect, wall panels of the windowed compartment have flaps which are destructively engaged to other panels thereof to provide a substantially inaccessible display compartment and one of the wall panels provides a hinged closure in the other compartment to provide a readily accessible unwindowed compartment for placement of other items. The hinged closure may be an entire wall panel spaced from the partition wall or it may be a portion of one of the wall panels spaced

2

to the unwindowed side of the partition wall, and preferably is of the tuck-flap type.

The window may have a plurality of folds therein and may, in fact, be a tubular member with the frame provided by a pair of cap members on the ends of such a tubular window structure. One of the cap members may be dimensioned larger than the other and is provided with a partition wall panel therein extending parallel to and spaced from the end wall thereof to provide an unwindowed compartment within the interior of the cap member. Preferably, the frame member is integrally formed of paperboard sheet material and the window aperture is removed from the confines thereof for a generally stronger structure which may be readily and economically fabricated.

By use of the semi-rigid synthetic plastic sheet material and securing it to the paperboard frame, a relatively high strength windowed container is obtained. The container is rapidly and easily erected from a blank comprised of a window of semi-rigid synthetic plastic sheet material which is secured to a frame of relatively rigid and opaque sheet material which overlaps at least two opposed side margins of the window and has a plurality of weakening lines therein defining folds to be made in forming the side walls of the container and a partition wall which will divide the interior of the container into two compartments. At least one of the weakening lines intersects the side margins of the window and the partition wall portion of the frame is spaced from the window so that the one compartment will be unwindowed. The partition wall portion has a flap thereon which will engage with one of the side walls of the container to maintain the partition wall in position. Preferably, wall portions of the frame providing the windowed compartment have flaps hingedly connected thereto by weakening lines which may be destructively engaged to other wall portions thereof to provide a substantially inaccessible windowed compartment and a wall portion of the blank providing the unwindowed compartment has a tuck flap hingedly connected thereto by a weakening line to provide a hinged closure for ready access.

For rapid and convenient cold-folding of the blank, the techniques disclosed in applicant's copending United States patent application Serial Number 191,018, filed April 30, 1962, and entitled Container and Method of Making Same, may be utilized or the window may be secured to the frame at one side of the fold line only to permit relative slippage between the window on the other side of the fold line and the other panels of the frame during the folding process. A general disclosure for a method and apparatus for cold-folding unscored synthetic plastic sheet material is found in applicant's United States Patent Number 2,954,725, issued October 4, 1960, and entitled Method and Apparatus for Folding Plastic Sheet Stock. To permit folding of the container on conventional folding equipment, the window may be scored along the fold line albeit with loss in strength.

Referring now in detail to the drawings, FIGURES 1-3 illustrate a six-sided container embodying the present invention and having a frame of relatively rigid and opaque sheet material, such as paperboard, generally designated by the numeral 2, and a folded window of semi-rigid synthetic plastic sheet material generally designated by the numeral 4.

As best seen in the blank illustrated in FIGURE 3, the frame 2 is integrally formed and is provided with transverse score or weakening lines 6 and cut so as to define and provide in the erected container a top wall panel 8, a front wall panel 10, a bottom wall panel 12, a rear wall panel 14, a spacing panel 16, a partition wall panel 18 and a glue flap 20. These transverse panels provide a generally rectangular body for the erected container with the interior divided by the partition wall

panel 18 into a windowed compartment generally designated by the numeral 22 and a smaller unwindowed compartment generally designated by the numeral 24.

The side walls of the container are defined by cuts and longitudinal score lines 26 which provide the side wall panel portions 28 hingedly connected to the bottom wall panel 12 adjacent the front wall panel 10, and by side closure portions 30 hingedly connected to the top wall panel 8 outwardly of the window 4. Tuck flaps 32 hingedly connected along the weakening lines to the ends of the closure portions 30 cooperate with the dust flaps 34, 36 hingedly connected to the rear wall panel 14 and partition wall panel 18 to provide readily releasable tuck-flap type closures for easy access to the unwindowed compartment 24. Outer glue flaps 38 and side glue flaps 40, 42 are hingedly connected along weakening lines to the side wall panel portions 28 for engagement by adhesive (not shown) to the top wall panel 8, the front wall panel 10 and the partition wall panel 18 to maintain the container in erected position and render the windowed compartment 22 substantially inaccessible except upon destruction of the container.

In the illustrated embodiment, the frame 2 has a window aperture 44 therein of generally rectangular configuration which extends through the portion of the top wall panel 8 overlying the windowed compartment 22 and into the front wall panel 10 across the score line 6a defining the interconnection therebetween.

Referring now in detail to the window 4, the configuration thereof also is best seen in the blank illustrated in FIGURE 3. The window 4 is of substantially rectangular configuration and is of larger dimension than the window aperture 44 so that marginal portions of the frame 2 adjacent the window aperture 44 overlap the corresponding marginal portions thereof. As seen in FIGURE 1, the window 4 is folded about the linear fold line 46 registering with the weakening line 6a defining the interconnection between the top and front wall panels 8, 10 to form a top wall portion 48 and a front wall portion 50.

In this embodiment, the thickness of the plastic sheet material at the fold line is accommodated in accordance with the teachings of the aforementioned copending United States patent application Serial Number 191,018 by providing notched-out portions 52 in the window at the fold line 46 and inwardly projecting finger portions 54 on the frame at the weakening line 6a which overlap the margins of the notched-out portions 52. A layer of adhesive shown by the stippling designated by the numeral 56 in FIGURE 3 bonds the window 4 to the frame 2 along the overlapping marginal portions but terminates adjacent the finger portions 54 so as to permit relative slippage thereat between the window and frame.

Alternatively, the window may be secured to the top wall panel 8 only so that relative slippage between the front wall portion 50 of the window 4 and the front wall panel 10 may occur upon folding so as to accommodate the thickness of the synthetic plastic sheet material at the fold line 46 by downward displacement.

Although cold-folding of an unscorched blank in accordance with applicant's aforementioned United States Patent Number 2,954,725 is preferable for greater strength, scoring of the plastic sheet material along the fold line 46 may also be employed with some weakening of the plastic sheet material as previously stated.

Referring now to the embodiment shown in FIGURES 4 and 5, the frame is comprised of a first cap member generally indicated by the numeral 102 and a second cap member spaced therefrom and generally indicated by the numeral 104. The cap members 102, 104 each are cut and provided with transverse score or weakening lines 106 which define the four side wall panels 108, 110, 112 and 114. The cap 102 is of larger dimension than the cap 104 and additionally is cut to provide a connecting flap 116 hingedly connected at the fold line 106a to one

end thereof and a glue flap 118 hingedly connected at the fold line 106b to the other end thereof.

Longitudinal score or weakening lines 120 define dust flaps 122, 124 hingedly connected to the side wall panels 110, 114, an end wall closure panel 126 on the cap member 102 which is hingedly connected to the side wall panel 108 and has a tuck flap 128 at the outer end thereof, and a pair of relatively narrow end wall closure panels 130, 132 on the cap member 104 which are hingedly connected to the side wall panels 112, 113. The longitudinal score lines 120 also define an elongated partition wall panel 134 and a glue flap 136 at the outer end thereof.

The window generally designated by the numeral 140 is formed of semi-rigid synthetic plastic sheet material and has curvilinear notches 142 at the intended fold lines 144 generally in alignment with the transverse score lines 106 of the paperboard frame. The cap members 102, 104 overlap the opposed edges of the window 140 and have inwardly projecting finger portions 146 which overlap the margins of the notches 142 in the window. As in the embodiment of FIGURES 1-3, the adhesive layer 147 bonding the window 140 to the cap members 102 and 104 and shown by the stippling in FIGURE 5 terminates adjacent the finger portions 146 to permit relative slippage therebetween.

When the blank is erected, the window 140 is provided with linear folds 144 which are generally aligned with the folds of the frame and results in a tubular window element having side wall portions 148, 150, 152 and 154. To maintain strength in the assembly, a locking flap portion 156 is preferably formed on the side wall portion 148 and secured to the side wall portion 154 by adhesive, heat-sealing or other suitable means (not shown). The end wall closure panels 130, 132 of the cap member 104 are secured to the dust flaps 122, 124 by adhesive (not shown) to produce a destructively engaged end wall closure for the windowed compartment. The glue flap 118 of the cap member 102 is secured to the side wall panel 108 by adhesive (not shown) and the connecting panel 116 is folded against the surface of the side wall panel 114 and the partition wall panel 134 extends across the interior of the cap member 102 and is secured to the side wall panel 110 by the glue flap 136 and adhesive (not shown). A readily released hinged tuck-type closure for the cap member 102 is provided by the end wall closure panel 126 and the dust flaps 122, 124. In this manner, a readily accessible unwindowed compartment is provided within the cap member 102.

The frame may be readily fabricated from paperboard sheet material of 12 to 50 mils in thickness, which provides ample rigidity for this purpose. Since the paperboard may be dyed or printed readily, wide variations in appearance of the container are possible.

The synthetic plastic sheet material employed for the window should be semi-rigid with sufficient flexibility to accommodate stresses and impacts occurring during normal usage. The material preferably should have the characteristics of being foldable in accordance with the method of the aforementioned United States Patent Number 2,954,725 and of substantially retaining a fold made therein to permit cold-folding in accordance therewith for rapid operation with unscorched blanks to provide high-strength folds.

Exemplary of the various synthetic plastic sheetings which may be employed are biaxially oriented polystyrene, cellulose acetate, cellulose acetate butyrate, polyvinyl chloride-acetate copolymer, polyethylene and polypropylene. As a specific example of a highly advantageous material, biaxially oriented polystyrene of about 5 to 15 mils has been particularly effective because of its clarity, high strength and semi-rigidity coupled with sufficient resiliency and flexibility to provide durable folds and resistance to normal impacts.

As can be readily appreciated, the present invention provides a plural compartment container having a windowed

compartment for displaying goods received therein and an unwindowed compartment which may be readily opened for inserting accessory items. The windowed compartment may be substantially inaccessible to prevent pilfering or damage to the displayed goods and the container is relatively strong by reason of the cooperation between the semi-rigid window material and relatively rigid frame material. This relatively strong and durable container is easily folded and assembled from a single blank which is conveniently made from readily available and relatively inexpensive materials to provide a highly attractive plural compartment window container.

Having thus described the invention, I claim:

1. A plural compartment window container having a windowed compartment and an unwindowed compartment, said container having a frame of relatively rigid and opaque sheet material with a plurality of hingedly connected wall panels defining the several sides of the container and an interior partition wall dividing the interior of said container into two compartments, adjacent wall panels of one of said compartments having an aperture therein extending across the hinged interconnection therebetween, one of the other wall panels providing a hinged closure for the other of said compartments and the wall panels defining said one compartment being destructively engaged and providing a substantially inaccessible windowed compartment and a readily accessible unwindowed compartment, a window of semi-rigid synthetic plastic sheet material having a linear fold therein in general alignment with the hinged interconnection between said apertured adjacent wall panels, said adjacent panels of the frame having marginal portions adjacent said aperture overlapping opposed side margins of said window generally normal to the direction of the fold in said window; and means securing said window to said frame along said overlapping side margins.

2. The container of claim 1 wherein said frame is formed of paperboard sheet material and said plastic sheet material is biaxially oriented polystyrene of about 5 to 15 mils thickness.

3. A plural compartment window container having a windowed compartment and an unwindowed compartment, said container having a frame of relatively rigid and opaque sheet material, a window of transparent, semi-rigid sheet material and means securing said window to said frame, said frame having a plurality of hingedly connected wall panels providing the top, bottom, side and end walls of said container and a partition wall extending across the interior of said container intermediate said end walls dividing the interior of said container into two compartments, said frame having a flap hingedly connected to said partition wall panel engaged to one of the other of said wall panels maintaining said partition wall panel in position, adjacent wall panels spaced towards one end of said container from said partition wall panel having a window aperture therein extending across the hinged interconnection therebetween, the marginal portions of said adjacent wall panels generally normal to the hinged connection therebetween overlapping opposed side margins of said window and said window having a linear fold therein in general alignment with the hinged connection between said adjacent panels, one of said wall panels towards the other end of said container from said partition wall providing a hinged closure for the unwindowed compartment to permit ready access thereto, said frame having flaps hingedly connected to a plurality of wall panels providing the windowed compartment destructively engaged with other wall panels to render said windowed compartment substantially inaccessible and said means securing said window to said frame along said overlapping side margins.

4. The container of claim 3 wherein said frame is integrally formed of paperboard sheet material.

5. A plural compartment container having a windowed compartment and an unwindowed compartment, said container having a frame of relatively rigid and opaque sheet

material and a window of semi-rigid synthetic plastic sheet material formed of a pair of spaced-apart cap members each having a plurality of hingedly connected wall panels defining top, bottom, end and a pair of side wall panel portions, one of said cap members having an interior partition wall panel extending parallel to and spaced from the end wall panel thereof but spaced inwardly of the opposite end of said one cap member providing an unwindowed compartment therein, said interior partition wall panel being hingedly connected to one of the other panels of said one cap member and engaged to another maintaining said partition wall panel in position said end wall panel of said one cap member being releasably engaged in closed position and providing a hinged closure for a readily accessible unwindowed compartment and said one end wall panel of the other of said cap members being destructively engaged with another of the wall panels thereof and providing a substantially inaccessible windowed compartment; a tubular window member of semi-rigid synthetic plastic sheet material having a plurality of linear folds therein generally aligned with the hinged interconnections between the side and top and bottom wall panels of said cap members, the opposed margins of the side, bottom and top wall portions of said cap members overlapping the edges of said tubular plastic window; and means securing said window to said frame along said overlapping margins.

6. A six-sided plural compartment window container having a windowed compartment and an unwindowed compartment, said container having a window of semi-rigid synthetic plastic sheet material having a linear fold therein; an integrally formed frame of relatively rigid and opaque sheet material with a plurality of hingedly connected wall panels defining the six sides of the container and an interior partition wall dividing the interior of the container into two compartments, said frame having a hinged flap on said partition wall panel secured to another of said wall panels maintaining said partition panel in position, said frame having an aperture therein to one side of said partition wall panel and extending into adjacent wall panels about the hinged interconnection therebetween, said aperture generally conforming to the periphery of said window and being of lesser dimension providing marginal portions on said frame adjacent said aperture overlapping the edges of said window, one of the wall panels of said container providing a hinged closure to the other side of said partition wall panel which is releasably engaged with another of said wall panels providing a readily accessible unwindowed compartment, said frame having flaps hingedly connected to wall panels to said one side of said partition wall panel destructively engaged to other of said wall panels providing a substantially inaccessible windowed compartment; and means securing said window to said frame along said overlapping marginal portions.

7. The container of claim 6 wherein said opaque sheet material is paperboard and said synthetic plastic sheet material is biaxially oriented polystyrene of about 5 to 15 mils in thickness.

8. A blank for a six-sided plural compartment container with a windowed compartment and an unwindowed compartment, said blank comprising an integrally formed window of synthetic plastic sheet material; an integrally formed frame of paperboard sheet material having an aperture therein generally conforming to the periphery of said window and of lesser dimension with marginal portions about said aperture overlapping the side margins of said window, said frame having weakening lines therein defining folds to be made in forming the six sides of the container and a partition wall dividing the interior of the container into two compartments with at least one of said weakening lines intersecting the side margins of said window, the partition wall portion of said frame being spaced from said window and having a flap thereon for engagement with one of the side walls of the container to maintain the partition wall in position upon erection of the blank to divide the interior of the erected container into a

windowed compartment and an unwindowed compartment, said frame having additional weakening lines therein defining a tuck flap on a side wall portion spaced from said window to provide a disengageable closure for the unwindowed compartment and weakening lines defining flaps on side wall portions adjacent said window for destructive engagement to other side wall portions to provide a substantially inaccessible windowed compartment; and means securing said window to said frame along said overlapping margins.

9. The blank of claim 8 wherein said opaque sheet material is paperboard and said synthetic plastic sheet material is biaxially oriented polystyrene of about 5 to 15 mils in thickness.
